HIGHWAY WARNING SIGN

Glen K. Phillippi, Moscow, Idaho

Application May 21, 1951, Serial No. 15,270

Term of patent 7 years

(Cl. D72—1)

To all whom it may concern:

Be it known that I, Glen K. Phillippi, a citizen of the United States, residing at Moscow, in the county of Latah, and State of Idaho, have invented a new, original, and ornamental Design for a Highway Warning Sign, of which the following is a specification, reference being had to the accompanying drawing, forming a part thereof.

In the drawing:

Figure 1 is a front elevational view of a highway warning sign, showing my new design;

Figure 2 is an edge elevational view of the highway warning sign, looking from right to left of Figure 1, and

Figure 3 is a fragmentary sectional view of a portion of the highway warning sign taken substantially along a plane as indicated by the line 3—3 of Figure 1.

I claim:

The ornamental design for a highway warning sign, substantially as shown.

GLEN K. PHILLIPPI.
